UNITED STATES PATENT OFFICE.

JONAS H. HITTLE, OF MACKINAW, ILLINOIS.

HARNESS-HOOK.

No. 857,241.

Specification of Letters Patent.

Patented June 18, 1907.

Application filed July 2, 1906. Serial No. 324,416.

To all whom it may concern:

Be it known that I, JONAS H. HITTLE, a citizen of the United States, residing at Mackinaw, in the county of Tazewell and State of Illinois, have invented certain new and useful Improvements in Harness-Hooks, and I do declare the following to be a full, clear, and exact description of the invention, such as will enable others skilled in the art to which it appertains to make and use the same.

This invention relates to improvements in harness hooks.

The object of the invention is to provide a harness hook having means whereby the harness will be securely held in place on the hooks, means being provided whereby the hook may be swung to an out-of-the-way position when not in use.

With the above and other objects in view, the invention consists of certain novel features of construction, combination and arrangement of parts, as will be hereinafter described and claimed.

In the accompanying drawings:—Figure 1 is a perspective view of a harness hook constructed in accordance with my invention; Fig. 2 is a vertical, longitudinal sectional view of the same, showing the keeper in closed position in full lines; Fig. 3 is a detail, perspective view of the keeper; and Fig. 4 is a view similar to Fig. 2, showing the keeper in open position for the removal of the harness from the hook.

Referring more particularly to the drawings, 1 denotes the hook, which consists of a lower supporting bar 2 having at one end an integrally formed upwardly-projecting pintle or pivot bolt 3, which is provided on its upper end with an enlargement 4, which forms an offset or shoulder 5. The lower portion of the pintle or pivot bolt 3 between the shoulder 5 and the bar 2 of the hook is adapted to be engaged by a clip 6, by means of which the hook is pivotally connected with the wall or other support, whereby said hook may be swung laterally in either direction to an out-of-the-way position when not in use.

Formed integral with the upper end and projecting outwardly substantially parallel to the bar 2 is a guard arm 7, the outer end of which is forked or bifurcated, to present fingers. In the outer terminals of the fingers is arranged a bolt 9, on which is pivotally

mounted a keeper or retaining bar 10. The keeper consists of a flat bar slightly tapered on the sides towards one end and provided on one side adjacent to its other end with an integrally formed malleable tongue 11, which is adapted to be bent into the form of an eye 12 around the bolt 9, thereby pivotally connecting said keeper thereto. In the upper side of the bar 2 adjacent to its outer end is formed a recess 13, the bottom or lower wall of which inclines downwardly toward the end 65 of the bar, as clearly shown in Fig. 2. When the keeper is in operative position, its free or reduced end is adapted to engage with recess 13, as shown in full lines in Fig. 2.

When it is desired to place the harness on the hook, the keeper is swung upwardly through the bifurcated outer end of the guard arm, thereby permitting the harness to be slipped onto the supporting bar 2, after which the keeper is swung downwardly until the lower tapered end 14 is seated in the recess 13, wherein the same is held against outward movement, thereby securely holding the harness on the bar 2. When not in use, the hook may be swung in either direction in 80 the supporting clip 6 to an out-of-the-way position.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as defined by the appended claims.

Having thus described my invention, what I claim as new and desire to secure by Letters-Patent, is:—

1. A harness hook comprising a supporting bar having a pintle at one end and a locking recess at its other end, a guard arm carried by the pintle and disposed in substantial parallelism with the bar and having its free end provided with spaced fingers carrying a bolt, and a keeper having an eye to engage the bolt and an end to engage the locking recess.

2. A harness hook comprising a supporting bar provided with a locking recess, a guard arm provided with spaced fingers, a

pintle connecting the bar and the arm and provided with a bearing shoulder, a clip to engage the pintle between the shoulder and the supporting bar, and a keeper pivoted between the fingers and having one end arranged to engage the locking recess.

In testimony whereof I have hereunto set

my hand in presence of two subscribing witnesses.

JONAS H. HITTLE.
